FAUCET HANDLE

Stephen A. Young, Delphi, Ind.

Application May 27, 1954, Serial No. 30,684

Term of patent 14 years

(Cl. D91—3)

Fig. 1

I claim:

The ornamental design for a faucet handle, substantially as shown.
